UNITED STATES PATENT OFFICE.

E. HALL COVEL, OF NEW YORK, N. Y.

IMPROVEMENT IN APPARATUS FOR DISINFECTING VESSELS.

Specification forming part of Letters Patent No. 42,464, dated April 26, 1864.

To all whom it may concern:

Be it known that I, E. HALL COVEL, of the city of New York, in the State of New York, have invented a certain new and useful improvement, being an Improved Mode of Disinfecting Vessels; and I do hereby declare that the following is a full, clear, and exact description of the same, reference being had to the accompanying drawings, and to the letters and marks thereon.

My invention is based upon the fact that extremes of temperature destroy infectious and contagious elements; and my invention relates to the use of heated air for removing the elements of contagion and infection from vessels or chambers or inclosures.

The drawings forming part of this specification show the means I use for disinfecting a vessel afloat, as at quarantine or in harbor, but, as is evident, other means may be used for vessels under other circumstance, or for chambers, the means being adapted to the conditions of the occasion.

By these drawings a vessel, *a*, is shown, with a furnace or fire-box, *b*, a tubular boiler, *c*, with its smoke-stack *d*, Figure 1 being a view looking down upon the vessel, and Fig. 2 being a view by transverse section at the red line of Fig 1.

The products of combustion from the furnace will pass around the boiler and escape through the smoke-stack, and the boiler will be provided with the usual supply and escape pipes, safety-valve, gage, &c.

It will be seen that the one end of the boiler is covered, *e*, the cover having attached to it an air tube or pipe, *f*, and that the other end of the boiler is also covered by a conical-shaped cover, *g*, having within it a blower or exhauster, *h*. From the end of the cover *g* a pipe will be continued, as also from the end of the pipe *f*, which, in case the means are being applied to a vessel floating, will, for the part at least, be elastic or india-rubber pipes, so

as to allow of the vessel's motion by the waves without injuring the pipes. Both *h* *e* pipes will terminate in the vessel or chamber to be purified, and thus, when the apparatus is in operation and the vessel or chamber closed, the air will be drawn from the vessel, passed through the tubes of the boiler, heated up to a high degree of heat, and disinfected and forced back into the vessel, the force employed being sufficient to give that degree of compression to the heated air as shall make it enter into all the recesses of the vessel or chamber.

In some instances the fire or heat may be applied directly to the tubes or space for heating the vitiated air—*i. e.*, there will be no water around the tubes in which the air is heated, they being exposed to the fire of the furnace or fire-box *b* direct, and, of course, no cylinder or shell will be needed around the tubes. The degree of heat will in some cases be higher than in others, due to the amount and character of the infection or contagion, and in some instances it may be deemed best to force into the vessel or chamber fresh air heated to a high degree, the one pipe then being open to the atmosphere, while the other will be open in the vessel or chamber, and the exit of the air from the vessel or chamber so regulated that the proper degree of compression of the air in the vessel or chamber will be maintained. In this way the infected air will be driven out of the vessel.

What I claim as my invention, and desire to secure by Letters Patent, is—

Disinfecting vessels, chambers, &c., by forcing the highly-heated air into and circulating it through them, substantially as herein set forth.

E. HALL COVEL.
